UNITED STATES PATENT OFFICE.

ALFRED P. SEIDELL, OF BLOOMFIELD, NEW JERSEY, ASSIGNOR TO ORANGE LIGHTING FIXTURE MANUFACTURING CO., A CORPORATION OF NEW JERSEY.

DESIGN FOR A LIGHTING-FIXTURE PLATE.

Application filed February 5, 1927. Serial No. 20,627. Term of patent 7 years.

To all whom it may concern:

Be it known that I, ALFRED P. SEIDELL, a citizen of the United States, and a resident of Bloomfield, county of Essex, and State of New Jersey, have invented a new, original, and ornamental Design for Lighting-Fixture Plates, of which the following is a specification, reference being had to the drawing forming a part hereof.

In these drawings:

Figure 1 is an inverted plan view of the lighting fixture plate, the part shown in full

line outline being ornamented in the same manner as the part more fully illustrated; and

Figure 2 is a side view of the same, the part shown in full line outline being ornamented in the same manner as the part more fully illustrated.

I claim:

The ornamental design for a lighting fixture plate substantially as shown and described.

ALFRED P. SEIDELL.
